UNITED STATES PATENT OFFICE.

ERNEST H. JACOBS, OF CHICAGO, ILLINOIS, ASSIGNOR TO ELECTRICAL ENGINEERS EQUIPMENT COMPANY, OF CHICAGO, ILLINOIS, A CORPORATION OF ILLINOIS.

POLE-TOP SWITCH.

1,367,188.

Specification of Letters Patent.

Patented Feb. 1, 1921.

Application filed April 29, 1918. Serial No. 231,548.

To all whom it may concern:

Be it known that I, ERNEST H. JACOBS, a citizen of the United States, residing at Chicago, in the county of Cook and State of Illinois, have invented a certain new and useful Improvement in Pole-Top Switches, of which the following is a full, clear, concise, and exact description, reference being had to the accompanying drawings, forming 10 a part of this specification.

My invention relates to pole top switches. Switches of this class are generally employed for interrupting the current flow in a transmission line at power houses, sub-stations and at transformer towers along the line. Such switches usually are of the quick break, open air type. They are usually mounted on a tower adjacent the sub-station, or upon a frame on top of the station. The 20 switch is operated from a distance by an arrangement of rods and levers extending to a suitable operating handle in convenient position at the foot of the tower or other supporting structure. The present invention provides a movable switch element pivoted centrally between the two switch terminals and arranged to be rotated laterally into or out of contact with both terminals simultaneously.

Switches of the above type are simple, inexpensive and rugged, and are in demand for outdoor installations, particularly where an oil circuit breaker would be impracticable.

My improved switch is of the above general type and is further characterized by certain novel features adding to its reliability and efficiency.

The switch terminals and rotatable switch 40 member are supported on insulators which are adjustably mounted on a supporting frame whereby they may be adjusted relative to each other. Further adjustment is provided to properly align the switch terminals and the rotatable switch members.

The clamps and insulators are preferably universal and interchangeable, of a form described in Patent No. 1,274,555, issued to me, August 6", 1918.

Another feature of the present invention resides in the spring mounting and the weather protection of the switch jaws. The switch jaws are mounted for a particular 50 rocking motion, adapting them to maximum area of contact. They are also protected

against accumulations of sleet and ice by a shield or hood which closely houses the jaws, yet does not interfere with their switching operation.

Another feature is embodied in the construction of the rotatable switch arm. This arm has switch blades or contacts pivoted to its ends and has flexible conductors extending along the arm and securely attached to the pivoted switch blades or contacts. The 60 main current flow passes through the flexible conductors and the switch blades or contacts. The arc caused by opening the switch is carried by horns mounted on the terminals and on the rotatable switch arm. These 70 horns are pivotally mounted under spring tension, which insures the proper period of contact and separation to relieve the main switch contacts of all arcing.

Other features residing in the construction and arrangement of parts will be apparent from the following detailed description. Some of the improvements in the present application are applicable to switches of other types, and I do not, therefore, intend to limit these improvements to the particular form of switch herein shown and described.

In the accompanying drawings, in which I have shown one preferred embodiment of 85 my invention,

Figure 1 is an elevational view of the pole top switch, parts being shown in section;

Fig. 2 is an enlarged elevational view of one of the switch terminals and the co- 90 operating movable contact, parts being shown in section;

Fig. 3 is a fragmentary continuation of Fig. 2 with the exception that its plane is at right angles to Fig. 2;

Fig. 4 is a plan view of one of the switch terminals showing the sleet hood and horn electrode;

Fig. 5 is a longitudinal sectional view of the switch terminal;

Fig. 6 is a transverse sectional view of the switch terminal;

Fig. 7 is an enlarged section taken on the line 7—7 of Fig. 1; and

Fig. 8 is a plan view of one of the socket 105 insulator clamps separated.

The mounting for the switch consists of two parallel pipes 10—10, which usually comprise part of a frame superstructure for supporting a number of electrical fittings. 110

The insulators 11, 12 and 13 for mounting the switch terminals 14, 15 and rotatable switch arm 16 respectively, are supported upon base plates 17 seated astride the pipes 10. These plates have extending claws 18 which partly embrace the pipes 10 and serve to guide the plates 17 along the pipes.

A pair of crabs 19 are slung from the ends of each plate by bolts 21 which pass 10 through ears 22 in the plate and through bosses 23 on the crabs. The crabs have claws for gripping the under sides of the pipes 10, as shown in Fig. 3. The plates 17 can be clamped at any desired point 15 along the pipes 10 by means of the bolts 21.

The insulators 11, 12 and 13 are of the petticoat type, particularly adapted for outdoor service, and have circumferential beads of substantially the same diameter 20 formed in their upper and lower ends. Universal insulator clamps 24 engage the lower beads and are bolted to the plates 17 and 26 by four feet 25 integral with each clamp.

25 These clamps comprise two semi-circular clamping bands which are bolted together by bolts 27 passing through lugs 28 extending out from the ends of the bands. The middle insulator 13 is reinforced by a pin 29, shown in dotted lines, which is cemented in a socket in the center of the insulator and which has radial arms rigidly attached to the plate 26. This pin prevents turning of the insulator 13 in the clamp 30 35 during rotation of the switch arm 16, and moreover braces the insulator against tilting in the clamp. This pin and the insulator clamp 24 are described in my co-pending application. The other insulators 40 11 and 12 may be provided with pins of this type if desired.

The plate 26 supporting the middle insulator, is bolted to another plate 31 which has an annular recess fitting over a hub 45 32 projecting up from the surface of the base plate 17, and has a bearing stud 33 journaled in a boss formed in the plate 17. A nut 34 threads over the end of the bearing stud 33.

50 Clamped to the upper bead of the insulator 13 is another insulator clamp 35. This clamp is divided into two semi-circular bands which are clamped together by bolts 36 passing through lugs extending from 55 the ends of the bands.

The switch arm 16 is supported across the top of the insulator 13 by means of a ribbed plate 38, which is secured by bolts 39 to a socket plate on the top of the insulator 60 clamp 35. As shown in Fig. 7, the switch arm 16 consists of an inverted channel 41, the limbs of which seat on the outside of longitudinal ribs 38', formed on the plate 38. The channel 41 and the plate 38 are 65 rigidly clamped together by bolts 42, pass-

ing up through the webs of the plate and channel.

Extending from the ends of the channel 41 are the links 44 which bear the switch blades 45. These links are pivoted in the 70 channel 41 upon bolts 46 and the two links are electrically connected by the flexible copper ribbons 47 extending through the channel 41. These copper ribbons are perforated for the passage of the bolt 46 and 75 are disposed above and below each link 44. The link 44 and ribbons 47 are maintained in firm contact by spring washers 48 above and below the ribbons.

The pivotal movement of the links 44 is 80 confined between the limbs of the channel 41, and each link is guided horizontally by a strap 49 riveted or welded to the channel 41 and extending across the open bottom of the same. The said 85 link 44 is narrower than the width of the channel in the bar 41 and being yieldingly clamped thereto at one end by the bolt 46 and spring washers 48 can swing from side to side in said channel, that is, it 90 is not rigid with the channel 41 and can yield slightly. In closing the switch the pivotal connections of the links 44 with the switch arm 16 permits the swinging of the arm to its closed position even though the 95 blades 45 might be entered between their respective jaws 68 and 69 before the arm reaches its limit, and in opening the switch the said limited pivotal movement permits the easy starting of the arm 16 before the 100 blades begin to move, thereby permitting a hammer action to free the device of ice, if such action is necessary. The flexible connections pressed upon the links 44 by the 105 spring washers 46 tend to hinder pivotal movement and also serve to provide a firm and sufficient contact at the pivotal connection.

The copper straps or ribbons 47 are less expensive and more readily attached than 110 flexible cables. I do not intend to exclude the use of flexible cables but find the ribbons more advantageous.

The switch terminals 14 and 15 are mounted in clamps 52 on the upper beads 115 of the insulators 11 and 12. As shown in Figs. 2 and 8, each clamp comprises the two semi-circular clamping bands 53 and 54, the former band having a split socket ring 55 formed integral therewith. These 120 bands are preferably slotted about their circumference as shown, to afford a slight resiliency whereby they may more readily conform to the annular bead 56 on the insulator. They are clamped upon this bead 125 by bolts 57 extending through apertured ears 58 projecting from the ends of the bands. These clamps may be made of malleable iron, brass or bronze. I find that brass or bronze is more yielding and has 130

less tendency to break the beads on the insulators.

Each switch terminal, consisting of the switch jaws, sleet hood and arcing horn, is supported upon a base plate 59. An annular plug 61 is attached to the under side of this plate by cap screws 62 and is arranged to thread down into the split socket ring 55 as indicated at 63. The socket ring 55 is split and has lugs 65 extending laterally from the ring on each side of the slot. A lug 66, projecting up from the band 54, is arranged to engage between the lugs 65 and to be clamped there by the bolt 67, which passes through alining holes in the three lugs.

When it is desired to adjust the switch terminal vertically, in order to bring the switch jaws into proper register with the switch blade 45, the entire terminal is rotated to screw the plug 61 up or down in the socket ring 55. The terminal is rigidly held in any adjusted position by tightening the bolt 67, which clamps the socket ring about the plug 61. The lug 66 is sufficiently narrow so as not to interfere with this action, the function of the lug being to connect the split side of the socket ring with the band 54.

Considering now the construction of the switch terminals and referring to Figs. 4, 5 and 6, a pair of switch jaws 68 and 69 are flexibly mounted between the base plate 59 and a hood 71, which extends out over the switch jaws and protects the same against collection of sleet and ice. The base 59 has integral bosses 72 and 73 extending up and supporting the hood 71. Bolts 74 pass down through the bosses 75 and 76 cast on the hood 71 and tap into the bosses 72 and 73.

The lower switch jaw 69 has an integral stud 77 which extends loosely into a socket 78 on the surface of the base 59. It will be noted that the base of the stud 77 has a beaded enlargement 77' which bears on the rim of the socket 78 and affords a spherical seating surface which will permit a slight rocking motion of the switch jaw 69 in any direction to adjust itself to the under surface of the switch blade 45.

A guiding lug 81 projects down from the jaw 69 and is adapted to abut against the raised socket 78. This lug receives the thrust produced when the switch blade 45 strikes the switch jaws. The upper jaw 68 has a similar lug 82 which is adapted to abut against a raised socket 83 formed on the under side of the sleet hood 71. A compression spring 85 is confined in this socket and encircles a stud 86, on the upper switch jaw 68.

To the rear ends of these switch jaws are riveted laminated copper ribbons 87. These ribbons engage above and below the connector block 88 which has the apertured boss portion 88' adapted for receiving the

line wire 89. A tongue, 95, projecting from the front end of the connector block acts as an abutment to limit the inward movement of the switch blade 45.

The connector block 88 and lower ribbon 87 seat in a channel shaped lug 91 which projects up integrally from the base 59 and has two marginal flanges embracing the sides of the ribbon and block, as best shown in Fig. 6. A similarly formed channel member 92 embraces the upper ribbon 87 and connector block 88. A bolt 93 passes down through the block 92, the ribbons and connector block and taps into the base 59.

The switch blade 45 in entering the switch jaws will raise the upper jaw 68 against the spring 85 and the two jaws, being flexibly mounted, will rock or tilt in any direction to accommodate the switch blade. Thus the action of the switch will always be free from jamming or from insecure or edge contact, even where irregularities exist in the mounting, due to slight inaccuracies in the insulators and the clamps. The front ends of the switch jaws are formed with flaring lips, 90 which are reinforced by ribs 98, these lips serving to properly guide the switch blade between the switch jaws. The upwardly inclined front end 71^a of the hood 71 projects out over the ends of the switch jaws 95 to protect the same, and the downwardly extending portions 71^b and 71^c along the side and rear of the hood, act as water sheds for partially inclosing the switch jaws.

The housing formed by the base member 100 59 and the cover or hood 71 forms a U-shape member within which are mounted pivotally the jaws 68 and 69. These jaws are pivoted at their centers along the sides or legs of the U and the jaws are connected to the 105 block 88 at the bottom of the U.

I have provided a pair of horns at each end of the switch to draw the arc on the break and thus relieve the switch blades and switch jaws of the injurious scarring resulting from this duty. A bracket 101 is secured by the bolts 46 at each end of the switch arm 16 and supports a horn 102. A coöperating horn 103 is pivotally mounted on each of the switch terminals, as shown 115 in the previously described figures. The bracket 104, supporting this horn, is formed integral with a sleeve hub 105, journaled between the base plate 59 and the sleet hood 71. The lower end of the sleeve 105 is open 120 and is journaled in a ring socket 106 formed integral with the base plate 59. A bolt 107 extends down through the sleet hood 71, and sleeve 105, and threads into the base 59. The spring 108 is coiled about the shank 125 of this bolt and has its ends attached to the base 59 and to the sleeve 105. The spring tends to revolve the sleeve 105 and bracket 104 counter clockwise as viewed in Fig. 4. The horn is normally held in the position 130

shown, by the engagement of a projection 109 on the surface of the hub 105, with a lug 111 on the ring socket 106.

The horns are composed of rods of half-round section, bent back to form a diverging horn gap. It will be noted that the horns 103, on the switch terminals, are bent both upwardly and laterally to provide the cam surfaces 112 and that the horns 102 are set at an angle to the switch arm so that with the switch closed both horns will occupy the relative positions illustrated in Fig. 4.

The switch is operated by the rotation of the arm 114, extending from the plate 31 (Fig. 1). A number of such switches may be operated simultaneously as in controlling a three phase circuit. The block 115 is swiveled to the end of this rod and has attachment with a rod 116 arranged to be reciprocated through a crank and shaft or any suitable mechanical means extending down from the pole or superstructure to a point accessible for operation.

In opening the switch from its closed position, as shown in Fig. 4, the switch blade carrying the horn 102, is swung to the left, the horn 102 strikes the cam surface 112 of the horn 103, and swings the horn 103, out of its path, the horn 103, being held in contact with the horn 102 by the spring 108. The horns remain in contact until after the blade 45 leaves the switch jaws and being the last part of the switch to separate, they carry the arc, and the final break of the arc occurs between the divergent upper ends of the horns. Upon closing the switch, the parts to make the contact first are the horns 102 and 103, the curved outer end of the horn 102 engages with the cam surface 112, of the horn 103, and pushes the horn 103 out of its path against the spring 108 and as the switch continues to close, the horn 102 slides along in contact with the horn 103, which is held in contact with the horn 102 by the spring 108, until the further rotation of the horn 103 is stopped by the stop pins 109 and 111, at which time the blade 45 has entered between the switch jaws 68 and 69, thus providing an ample path for the current. The further closing of the switch carries the blade 45 to its final position between jaws 68 and 69, and separates the horns 102 and 103, as shown in Fig. 4. Thus the horn electrodes always make contact first on closing the switch and break contact last, relieving the switch blades and jaws of arcing. The horns are preferably of a hard grade of iron and can be cheaply and easily renewed.

I do not intend to be limited to the particular details herein shown and described.

I claim:

1. In combination, a switch arm comprising

ing a channel member pivoted at its center for rotative movement, switch blades pivotally supported at the ends of said channel member, and a flexible conductor disposed in said channel member and having connection with said switch blades. 70

2. In combination, a switch arm comprising a main supporting member pivoted at its center for rotative movement, switch blades pivoted at the ends of said member, 75 and a flexible conductor strung along said member and having connection with said pivoted switch blades.

3. In combination, a pivoted switch arm, a switch blade pivotally supported at the 80 end of said switch arm, and a flexible conductor extending along said switch arm and having connection with said switch blade.

4. In combination, a switch arm comprising a main supporting member pivoted 85 at its center for rotative movement, switch blades on the ends of said member, a flexible conductor extending along said member and connecting said switch blades, said switch blades having pivotal movement at 90 the ends of said member, said flexible conductor tending to hinder said switch blades in their pivotal movement.

5. In combination, an insulator, a clamp on said insulator, a rotatable switch arm 95 supported on said clamp, said switch arm comprising a channel member, pivoted switch blades extending from the ends of said channel member, and a plurality of flexible conducting ribbons disposed in said 100 channel member and connecting said switch blades.

6. In combination, an insulator, a clamp on said insulator, a terminal supported on said clamp, and means for adjusting said 105 terminal vertically on said insulator.

7. In combination, an insulator, a clamp on said insulator, a socket in said clamp, and a terminal having a plug engaging in the 110 socket, whereby said terminal may be adjusted relative to said insulator.

8. In combination, an insulator, a clamp on said insulator, a threaded socket in said clamp, a terminal, a threaded plug on said terminal engaging in said socket, and means 115 for holding said plug in any adjusted position in said socket.

9. In combination, an insulator, a clamp on said insulator, a socket in said clamp, a terminal, a plug on said terminal, said plug 120 threading into said socket and means for contracting said socket about said plug to hold said terminal in any adjusted position.

10. In combination, a supporting member, a terminal mounted on said supporting member and plug and socket means for adjusting said terminal relative to said supporting member. 125

11. In a switch terminal, a housing comprising a base and a hood mounted thereon,

- switch jaws mounted between said base and said hood, and a horn gap electrode pivoted on said housing and extending above said hood.
- 5 12. In a switch terminal, a base, a pair of switch jaws mounted on the base, a hollow hub member pivotally mounted on said base, a bracket carried by the hub member, a horn gap electrode carried by said bracket and 10 extending above said switch jaw, a stop limiting the pivotal movement of said member in one direction, and a spring within said hub member yieldingly holding the hub member against the stop.
- 15 13. In combination, a terminal base, a pair of switch jaws mounted on said base, a protecting hood over said jaws, a bracket pivoted on said base and hood, an arcing horn supported in said bracket, and spring means 20 tending to hold said horn in a predetermined position.
14. In combination, a supporting member, insulators mounted for adjustable movement along said supporting member, switch terminals carried by said insulators, and means 25 for adjusting said terminals perpendicularly of said supporting member.
15. In a switch, a supporting member, a plurality of insulator units on said supporting member, each of said insulator units comprising a base member shiftable along said supporting member, an insulator mounted on said base member, a clamp on said insulator, a switch terminal attached to said clamp, 35 and means for adjusting said switch terminal relative to said clamp.
16. In combination, a supporting frame, insulators shiftable along said frame, switch terminals mounted on said insulators, a 40 switch arm centrally pivoted on one of said insulators, switch blades pivoted to the ends of said switch arm, switch jaws mounted on said switch terminals for receiving said blades, said switch jaws being self adjusting 45 to contact with said blade, horn gap electrodes on the ends of said switch arms, and coöperating electrodes pivotally mounted on said switch terminals.
17. In combination, a stationary contact, 50 a movable contact movable horizontally to and from engagement with the stationary contact, a horn electrode pivotally mounted on the stationary contact and extending vertically and a coöperating horn on the movable electrode extending vertically.
18. In combination, a stationary contact, 55 a movable contact movable horizontally to and from engagement with the stationary contact, a horn electrode pivotally mounted on the stationary contact and extending vertically, a horn on the movable electrode extending vertically, and a protected spring yieldingly holding the pivoted horn in the path of the horn on the movable contact.
- 60 19. In a switch device of the kind de-
- scribed, a horizontal switch arm comprising a channel bar having its open side down and pivoted at its center for rotative movement, switch blades pivotally supported at the ends of the bar, and a flexible conductor 70 disposed in said channel bar and having connections with said switch blades.
20. In a switch terminal, a base, a weather hood carried by the base, a pair of switch jaws carried by the base beneath said hood, 75 a hollow hub member pivotally mounted between the base and hood, a horn gap electrode carried by said hub member and projecting above said hood and a spring within said hub for yieldingly holding the hub member in one direction.
21. In an electric switch, a pair of opposed switch jaws, a switch frame, sockets and co-operating projections on the jaws and frame, a connector block and flexible connectors 85 connecting said jaws with said connector block.
22. In a switch terminal, a pair of opposed switch jaws, a switch frame, sockets on the frame and coöperating projections on the 90 jaws engaging in said sockets, a connector block, and flexible connectors connecting said jaws and said connector block.
23. In a switch terminal, a pair of opposed switch jaws, a housing within which 95 the jaws are mounted, sockets on said housing, and projections on the backs of the jaws engaging in said sockets, a spring between the housing and one of the jaws, pressing said jaws together, and flexible connectors 100 connecting said jaws to the housing.
24. In a switch terminal, a pair of opposed switch jaws, a switch frame, sockets on said frame and projections on backs of the jaws for entering said sockets, a connector 105 block, flexible connectors connecting the jaws to said block, the outer ends of the jaws being divergent to direct a blade between them, the said sockets and projections formed to permit the jaws to rock to accommodate themselves to the opposed surfaces of an interposed blade.
25. In a switch terminal, a pair of opposed switch jaws, a switch frame, coöperating sockets and projections on the frame 115 and jaws, spring means between the blades and frame for pressing said jaws toward each other, a connector block, flexible connectors connecting the jaws to said block, the outer ends of the jaws being divergent 120 to direct a switch blade between them, the sockets and projections formed to permit the jaws to rock to conform with the contacting surfaces of an interposed blade.
26. In a switch terminal, opposed switch 125 jaws, a switch frame, sockets on the frame and coöperating projections on the backs of the jaws for engaging in the sockets, one of the jaws movable from and toward the other jaw, a spring interposed between the mov- 130

- able jaw and the frame for yieldingly holding the movable jaw toward the other jaw, a conductor block carried by the frame, flexible means connecting said jaws with said block, the outer ends of the jaws provided with inclined surfaces for engagement with a switch blade for separating said jaws as a blade is inserted between them, the coöperating sockets and projections formed to permit the jaws to rock to follow the blade.
27. In a switch, two opposed switch jaws, a switch housing, means floatingly mounting the jaws on the housing, means yieldingly holding the jaws pressed toward each other and permitting them to separate when a switch blade is forced between them, and projections on the jaws for engagement with the housing to take the thrust of an entering blade.
28. In a switch, a housing, two opposed switch jaws, coöperating loosely fitting projections and sockets for loosely mounting the jaws on the housing, the jaws having divergent ends providing a wedge shaped mouth to receive a switch blade for entrance between the jaws, and projections on the jaws for engagement with the housing to transmit the impact of an entering blade.
29. In a switch, a housing, two opposed switch jaws, projections on the jaws, and sockets on the housing in which the projections are loosely engaged, spring means pressing said jaws toward each other, said jaws having divergent ends for wedgingly receiving a switch blade, and projections on the jaws adapted to engage said sockets to withstand the impact of an entering blade.
30. In a switch, a housing, two opposed switch jaws, coöperating projections and sockets on the jaws and housing loosely mounting the jaws on the housing, means yieldingly holding the jaws pressed together, flexible means connecting the jaws with the housing, said jaws having divergent ends for wedgingly receiving a switch blade, projections on the jaws for engaging the housing to withstand the impact of an entering blade, and a stop on the housing, independent of the jaws, for limiting the entering movement of the blade.
31. In a switch, a housing, two opposed switch jaws, coöperating projections and sockets on the jaws and housing loosely mounting the jaws on the housing, the forward ends of the jaws formed to wedgingly receive a switch blade for forcing said jaws apart, a spring for yieldingly holding said jaws toward each other, a connector block secured to the housing, flexible connectors spanning said block and secured to said jaws, said block positioned in the path of an entering blade and adapting to limit the inward movement thereof, said jaws free to conform to and with an interposed blade.
32. In combination, a U-shaped frame

member, a pair of switch jaws pivotally mounted at their centers on and between the legs of the U, and a stop member mounted on said frame member at the bottom of the U.

33. In combination, a U-shaped frame member, a pair of switch jaws mounted for universal rocking motion at their centers on and between the legs of the U and spring means tending to press said jaws together.

34. In combination, a U-shaped frame member, a pair of switch jaws pivotally mounted at their centers on and between the legs of the U, spring means for pressing said jaws together and flexible connecting means for connecting the inner ends of said jaws to a common terminal member.

35. In combination, a U-shaped frame member, a pair of switch jaws pivotally mounted at their centers for universal rocking motion on and between the legs of the U, a stop member at the rear end of said jaws, and flexible leads connecting the rear ends of the jaws to said stop member.

36. In combination, a pair of rigid floating switch jaws, a blade adapted to be thrust between the jaws, means for imposing pressure substantially centrally on said jaws to hold them yieldingly pressed toward each other and to grip the blade between them, a common terminal and flexible leads from the jaws to said common terminal and jaws having shoulders for preventing longitudinal displacement of the jaws by the entering blade.

37. In combination, a pair of rigid switch jaws having each a central projecting bearing member, supporting means lying on the outside of said jaws and having a socket for each of said bearing members and permitting of limited universal movement of the jaws, spring means tending to press said jaws together, a terminal mounted on said supporting means, and flexible means between said terminal and each of the switch jaws.

38. In combination, a pair of switch jaws, relatively stationary means upon which said jaws are loosely mounted substantially centrally for universal rocking motion, means holding said jaws yieldingly pressed toward each other, and a pivoted switch blade adapted to be forced between and gripped by said jaws.

39. In combination, a pair of switch jaws, a relatively stationary frame comprising a weather hood extending over said jaws and providing bearing means on the outside of each of said jaws, said jaws being pivoted substantially centrally for universal motion, means yieldingly holding said jaws toward each other, a terminal mounted on said frame member and flexible conductors connected to the inner ends of said jaws and said terminal.

40. In a switch, a pair of switch jaws, an external frame member embracing both of the jaws, said jaws having a central bearing on said frame member about which they are 5 mounted to rock, means yieldingly pressing the jaws together, a connector block, flexible connectors joining the jaws electrically to said block, a switch blade adapted to enter between the jaws and a stop on the connector block for limiting the entering movement of the blade.

41. In combination, a pair of switch jaws having engaging surfaces facing toward each other for engaging a switch blade, said 15 jaws having bearing projections on their rear or outer surfaces, said projections lying substantially centrally of the jaws, supporting means embracing said jaws and having sockets engaging the projecting bearings, 20 and means for yieldingly holding said jaws in engagement with a switch blade.

42. In combination, a pair of switch jaws having engaging surfaces facing toward each other for engaging a switch blade, said 25 jaws having bearing projections on their rear or outer surfaces, said projections lying substantially centrally of the jaws, supporting means embracing said jaws and having sockets engaging the projecting bearings, 30 means for yieldingly holding said jaws in engagement with a switch blade, a terminal member and flexible leads connecting the terminal member with said switch jaws.

43. In combination, a pair of switch jaws, 35 supporting means lying outside of and embracing both the jaws for holding the same, said jaws having universal movement on said supporting means, spring means between said supporting means and one of the 40 jaws for pressing the jaws toward each other, a stop block back of said jaws and flexible conductors connecting the jaws to the stop block.

44. In an electric switch, a pair of opposed switch jaws, a frame, one of said jaws and said frame having a coöperating socket and a projection, spring means for said jaw, a connector block mounted on said frame and a flexible conductor connecting said one 50 jaw and said block.

45. In combination, a pair of mounting bars spaced apart, a base member having claws for engaging said bars, an insulator having a pivot extending into said base and 55 lying between said bars, a switch arm car-

ried by said insulator, said switch arm being adapted to swing about said pivot and a clamp lying on each side of the pivot and having claws engaging the side of the bars opposite the claws of the base member. 60

46. In combination, a hollow switch arm comprising a rigid self supporting member mounted for pivotal movement, a contact blade mounted at one end of the switch arm and a conductor which is not self supporting 65 connected to the blade and being carried within and by the rigid member.

47. In an electric switch, a pair of rigid switch jaws lying opposite each other, a frame for supporting said switch jaws, one 70 of said jaws and said frame having co-operating means for permitting a lateral motion and a limited rocking motion of said one switch jaw, spring means for holding said jaws in contact with an interposed 75 switch blade, a connector block mounted on said frame and a flexible conductor connecting said one jaw and said block.

48. In combination, a pair of pipe supporting members spaced apart from each 80 other but lying substantially in parallel relation, a base member having claws for engaging said bars, a pin member pivoted in said base member centrally between the bars, clamping means lying on the opposite side 85 of said pipe members, said clamping means having claws engaging said bars for securing the base member to said bars, an insulator mounted on said pin and movable therewith and a conductor rigidly secured 90 to the top of the insulator and movable therewith about said pivot pin.

49. In combination, a pair of pipe members, terminal insulators clamped to said pipe members a suitable distance apart, a 95 pivotal insulator clamped to said pipe members between said terminal insulators, said pivotal insulator comprising a base clamped to the pipe members and a pivot pin mounted in the base member and secured to the 100 insulator, a switch blade mounted on the pivotal insulator, stationary contacts mounted on the terminal insulators, said contacts adapted to coöperate with the switch member and means permitting of independent 105 vertical adjustment of the contact members on the terminal insulators.

In witness whereof, I hereunto subscribe my name this 26th day of April, A. D. 1918.

ERNEST H. JACOBS.

It is hereby certified that in Letters Patent No. 1,367,188, granted February 1, 1921, upon the application of Ernest H. Jacobs, of Chicago, Illinois, for an improvement in "Pole-Top Switches," an error appears in the printed specification requiring correction as follows: Page 5, line 116, claim 25, for the word "blades" read *jaws*; and that the said Letters Patent should be read with this correction therein that the same may conform to the record of the case in the Patent Office.

Signed and sealed this 8th day of March, A. D., 1921.

[SEAL.]

M. H. COULSTON,

Commissioner of Patents.

Cl. 200—48.
